(57) **CLAIM**

The ornamental design for a control panel for a cable testing system, as shown and described.

DESCRIPTION

FIG 1.1 : is a front view of a first embodiment of a control panel for cable testing system showing my new design;

FIG 1.2 : is a perspective view thereof;

FIG 1.3 : is a top view thereof;

FIG 1.4 : is a left view thereof;

FIG 1.5 : is a right view thereof;

FIG 1.6 : is a bottom view thereof;

FIG 1.7 : is a back view thereof;

FIG 2.1 : is a front view of a second embodiment of the control panel for cable testing system;

FIG 2.2 : is a perspective thereof;

FIG 2.3 : is a top view thereof;

FIG 2.4 : is a left view thereof;

FIG 2.5 : is a right view thereof;

FIG 2.6 : is a bottom view thereof;

FIG 2.7 : is a back view thereof;

FIG 3.1 : is a front view of a third embodiment of the control panel for cable testing system;

FIG 3.2 : is a perspective view thereof;

FIG 3.3 : is a top view thereof;

FIG 3.4 : is a left view thereof;

FIG 3.5 : is a right view thereof;

FIG 7.1 : is a front view of a fourth embodiment of the control panel for cable testing system;

FIG 7.2 : is a perspective view thereof;

FIG 7.3 : is a top view thereof;

FIG 7.4 : is a left view thereof;

FIG 7.5 : is a right view thereof;

FIG 7.6 : is a bottom view thereof;

FIG 7.7 : is a back view thereof;

FIG 8.1 : is a front view of a fifth embodiment of the control panel for cable testing system;

FIG 8.2 : is a perspective view thereof;

FIG 8.3 : is a top view thereof; and

FIG 8.4 : is a bottom view thereof.

The broken lines shown in the drawings illustrate portions of the control panel for cable testing system that form no part of the claimed design.
